GARMENT MANUFACTURE

Philomena A. Montagna, Germantown, Pa.

Application April 25, 1945, Serial No. 590,166

1 Claim. (Cl. 2—243)

1

This invention relates to garment making and has particular reference to what is broadly termed "dressmaking" as it is carried out by the individual at home.

An object of the invention is to enable one not talented as a seamstress, one who is unskilled in the art of dressmaking as distinguished from flatwork, to make garments of all types and descriptions quickly, easily and cheaply at home.

Another object of the invention is to bring within the capacity of such a person various designs and fashions involving numerous types of functional and decorative trimming which are impossible to duplicate outside of the more expensive lines of garments, or which may be made at home as copies only at considerable expense in material and with a very substantial amount of skill in the matter of fitting, cutting and sewing.

As a corollary to the above, I have sought to place at the disposal of the great mass of people garments which in design, appearance and quality of texture have hitherto been available only to those able to afford the work of expensive designers and costumers, or possessed of ability and funds to purchase the various materials and make a copy of the desired garment.

A particular field of usefulness contemplated by the invention resides in children's garments. Designs and styles which in quantity and quality would ordinarily be quite outside the scope of the average family budget may be easily and quickly added at will to the wardrobe. Through my invention it becomes easy for anyone, no matter how unskilled in the art of pattern cutting and the general field of dressmaking, to outfit a family at very small cost with clothes styled, designed and trimmed in a manner hitherto available only to those able to afford them or able to make them from fashion book designs, paper patterns, etc.

This invention is predicated on the old idea of stamping on a sheet of garment fabric cutting lines delineating the various component portions of a composite garment, such as a dress, blouse, etc. Such component parts are usually the front, the back, the sleeves, the collar, the cuffs, etc., which are customarily assembled by a "dressmaker" to form the complete garment, and I recognize that plain fabrics so delineated with cutting lines and legends indicating the nature of each component portion of the garment and the manner in which they are to be assembled when cut from the fabric sheet are not broadly new. However, this idea has never been advanced to the point where it possesses any real utility because of the very narrow limits within which the broad idea as above expressed and taught in the prior art is applicable.

2

An object of my invention has been to carry this old idea forward to a point where it possesses real utility and to teach how it may be so basically improved that the results obtainable are tremendously beyond anything hitherto attainable and an entirely new process is involved as well as an entirely new starting material, permitting great ramifications in this particular field.

An important feature of the invention resides in the fact that various component portions of the garment as delineated by cutting lines on a garment fabric sheet have representations of trim material imprinted upon or otherwise associated with the fabric. These representations may be in contrasting or other colors, and the designs or imprints on each respective component are so located and contoured with respect to it and the other trim imprinted components that the respective designs are coordinated into an integral whole when the components are cut and assembled in the intended manner to fashion the completed garment.

For purposes of illustration, but by no means of limitation, I have selected a simple but attractive woman's blouse of that severity of design which tends to distinguish the well designed and executed garment from run-of-the-mill products. Such tailored garments are frequently softened or relieved by definitely positioned and well executed trim material. The garment illustrated is banded with parallel spaced pipings or bands in contrasting but harmonious colors. It will be noted that the garment is further distinguished by gathering at the waist and by shoulder ribbon bow appliqués in the same color contrast and order of color succession as the marginal bands.

This smartness of simplicity is frequently obtainable only in expensive garments and to reproduce them by hand is extremely tedious, time-consuming and very demanding as to skill. Of necessity this is true because by the usual practice of dressmaking the trim material must be added after the garment *per se* is completed. Through my invention a substantial facsimile insofar as appearance and style are concerned is obtainable by the simple expedient of purchasing a single piece of fabric on which the various component portions of the garment have been delineated by cutting lines, each component portion having imprinted thereon or otherwise suitably associated therewith in proper coordinated location the representation of desired trim material, cutting the components out of the fabric sheet and sewing them together.

Various other advantages and important features of the invention will be readily apparent from the following description taken in conjunction with the drawings, wherein like numerals

refer to like parts throughout the several figures, and wherein:

Figure 1 illustrates a finished garment and

Fig. 2 illustrates an integral fabric sheet from which the finished garment is made.

Referring now to the drawings, the garment or blouse is broadly designated by the numeral 10 and comprises a main body portion including a back and a front and sleeves 12 and 13. The material is gathered as indicated at 14 on opposite sides. The color banding is broadly indicated by the numeral 16 and the applique ribbon bows broadly by the numeral 18. Matching buttons are represented by the numeral 20.

Referring now more particularly to Fig. 2 of the drawings, it will be apparent that the main body portion of the blouse 10 is composed of a back component 22 and two front components 24 and 26, each of which, like other components, is delineated by cutting lines 28. In this particular instance a cutting line 28' is included which, while not a marginal line in the completed garment, must be cut to permit the gathering hitherto referred to and sufficiently indicated on the fabric layout, as will be apparent from the drawing.

Spaced bands which may be in contrasting colors as indicated on the drawing are imprinted upon predetermined portions of each of these component sections as indicated at 30, 32 and 34 and the applique shoulder ribbon bows are imprinted as indicated at 36, 38 and 40. As will be apparent from the drawing, the margin of each sleeve 12 is relieved by spaced bands which may be similar in color and order of succeeding colors to the bands 30, 32 and 34.

It is important to note that the bands and applique ribbon bows are positioned on the various component portions of the composite garment in predetermined respective locations and that these representations of trim material are so located and contoured with respect to the margins of each that when the components are assembled the respective representations or designs are coordinated into an integral whole. It will therefore be seen that, when the two front sections, respectively, are sewed to opposite sides of the back 22, the bandings thereon will form continuations of bandings identical in color and succession of color to the bandings 35 around the neck or throat of said back component 22, thus forming a continuous spaced band throat relief effect around the collar as clearly appears in Fig. 1 of the drawing. Of course the continuity of the bandings will be interrupted at seam lines, but to the naked eye the effect is one of uninterrupted continuity.

The fabric layout includes all the necessary components of the finished product such as the linings and/or facings 42 and 44 for the front margins of the blouse, a facing 46 for the back of the collar, and a back band or waist lining 48. Darts are indicated clearly as at 50 to aid in assembling the various components. All of these details are conventional.

The fabric sheet likewise includes a predetermined number of button coverings 52, here shown in the same color contrast and succession of color as the bandings, etc. The size of the buttons is clearly indicated on the fabric sheet and it is necessary only to cut the coverings out and use them as coverings for the size button indicated. The size of button is of course coordinated with the buttonhole indicated at 54 and the particular

point of button securement may be indicated by dots as shown at 56.

The design and trim representation associated with the fabric sheet described herein are relatively simple and of course it will be understood that the particular type of trim representation and the particular type of design are of no importance whatsoever insofar as this invention is concerned. The important feature is to associate any trim material representation and design with the various component portions of the composite garment in such manner that when assembled an integrated whole is obtained by the coordinated portions. It is likewise immaterial how the fabric sheet is produced, i. e., whether the fabric is run through lithograph, offset or any other type of press to obtain the desired predetermined imprint. It is also immaterial what type of fabric is used except insofar as it is suitable for the purpose, both as to quality and texture of fabric, and its receptivity characteristic with reference to the type of imprint desired.

While I have suggested in the foregoing description the feasibility of dye printing, the invention contemplates broadly the application in any manner of decorative trim to correlated portions of each component section of the finished garment as delineated by the cutting lines of the fabric sheet to provide absolutely finished units which need only be cut and sewed together by the most inexperienced in order to obtain results hitherto utterly unavailable without considerable expenditure of time, money and skill, or from the more costly garments.

What I claim is:

A new article of manufacture comprising a fabric sheet having independently delineated thereon, by cutting lines for each, the separate individual component portions of a selected complete garment of the type usually assembled by a dressmaker and legends indicating the nature of component parts and sufficient data to indicate the manner of their assembly, certain of said component portions having representations of trim material imprinted thereon to produce the effect of trim material separately applied to the fabric, each representation being so located and contoured with respect to its respective component that when the components are cut from the sheet and subsequently assembled the various trim material representations become coordinated into an integral whole, whereby the effect of such a garment previously assembled and subsequently so trimmed with separate material is obtained.

PHIOMENA A. MONTAGNA.
